UNITED STATES PATENT OFFICE.

HAROLD A. ROHRICH, OF TOLEDO, OHIO, ASSIGNOR TO THE OWENS BOTTLE COMPANY, OF TOLEDO, OHIO, A CORPORATION OF OHIO.

GLASS-FORMING MACHINE.

Application filed February 24, 1926. Serial No. 80,299.

My invention relates to improvements in machines for the manufacture of glassware, and particularly to a machine comprising a rotatable mold carriage including a series 5 of blank molds into which the charges of glass are introduced, and cooperating neck molds by which the bare blanks or parisons are suspended after being formed in the blank molds and after the latter have 10 opened.

An object of the present invention is to provide an improved means for simultaneously and uniformly cooling or chilling corresponding sides of a plurality of suspended blanks, such improved means being adapted to direct a plurality of sheet-like air jets from spaced orifices in order that the several blanks suspended from double, triple or other multiple molds may be treated 20 to retain them in true vertical positions.

The present invention is based upon the principle embodied in Patent No. 1,299,482, dated April 8, 1919, and through the revised structure herein disclosed, is, as above 25 stated, adaptable for use without structural alteration or adjustment, in connection with single, double or triple molds.

Other features and advantages will be apparent hereinafter.

In the accompanying drawings which illustrate the preferred construction embodying the principles of my invention:

Fig. 1 is a diagrammatic plan view of a rotary mold carriage and associated parts, 35 all of conventional form, the improved type of nozzle being illustrated in connection therewith.

Fig. 2 is a detailed vertical sectional view showing the relation of the blast nozzle, air 40 supply pipe, air flow control, and the suspended blank.

Fig. 3 is a detailed top plan view of the nozzle and air feed pipe.

Fig. 4 is a front elevation of the nozzle 45 and air feed pipe.

Fig. 5 is a transverse sectional view taken substantially on line V—V of Fig. 4.

Fig. 6 is a front end elevation of one of the mold carrying units, showing double 50 molds associated therewith.

The present invention is herein disclosed as applied to a machine of the type illustrated in Patent No. 1,185,687, dated June 6, 1916, and includes a mold carriage 7

which rotates continuously about a central 55 standard 8, and mounts a plurality of radiating heads or mold carrying units 9, upon each of which is arranged in the usual, or any preferred manner, single, double or multiple molds 9' which may be of conventional form. As in the Patent, 1,185,687, above referred to, the charge of molten glass is transferred as by suction from the glass tank 10 to the molds, and is then treated in the usual manner as a result of which, the 60 final form is assumed.

During the rotation of the mold carriage, there is a tendency of the suspended blanks to swing outwardly, due to unequal degrees of cooling as between the outer and inner 70 sides or portions of the blanks immediately below the neck, and in order to overcome this fault and maintain the blanks in truly vertical positions and at the same time provide for simultaneous cooling of a plurality 75 of blanks, as well as single blanks or parisons 9'', I employ a structure which may be described as follows:

This improved cooling or chilling means comprises, in its broadest form, an elongated 80 nozzle of sufficient length to approximately span one of the mold carrying units, the nozzle being so spaced from the points at which the blanks are suspended, that jets of air emitted from longitudinally spaced 85 orifices, coact with each other at the points of contact with the blanks to form a continuous or single substantially flat, sheet-like, cooling blast.

Each nozzle or head 11, as shown in Fig. 90 4, is provided at its medial point with an upwardly extended inlet neck 12, providing means for attachment of the nozzle to an air feed conduit 13, illustrated as consisting of several sections interconnected by elbows 95 14 and mounting at the upper end, a feed control valve 15, which, as shown in Fig. 2, is rigidly fixed to an adjacent portion of the carrying frame. Below this valve 15 in the air conveying pipe, is a pressure control 100 valve 13'.

As in Patent No. 1,299,482, above referred to, the valve 15 is adapted for intermittent operation by means of a stationary control cam 16 which acts upon a roller 17 carried 105 by the usual valve stem.

It will be noted that sets of jet orifices 18 are uniformly spaced with respect to each

other and to the inlet neck, such orifices preferably being declined forwardly from the juncture of the lower and front walls of the elongated hollow body, and of slot-like formation to effect emission of sheet-like blasts of air which increase in width toward the blank or blanks being cooled to such a degree that in effect a continuous flat blast impinges against the suspended charges.

10 In the formation of these orifices, I form integrally with the front wall 19 of the nozzle 11, a forwardly declined lip or flange 20 whose lower face extends through the bottom wall of the body forming at each 15 side of the inlet 12, a continuous slot 21 extending longitudinally of the lower wall and communicating therethrough with the interior of the body. This peculiar formation of the slot with respect to the flange, 20 results in the creation of a longitudinal shoulder 22 which forms an abutment adapted to contact with the adjacent edge of a base plate 23, this base plate, as shown, being provided with longitudinally spaced, 25 transversely extending ways or channels 24 which provide communication as between the interior of the body and the atmosphere. As is noted, these ways 24 are extremely shallow, with the result that orifices of slot-like configuration are formed for the purpose heretofore pointed out.

By reference to Figs. 4 and 5, it will be noted that the upstanding portions between the transverse channels, serve to close portions of the longitudinal slot 21 in the hollow body, thereby confining ejection of blasts of air to the uniformly spaced orifices.

At suitable points, machine screws, or like 40 fastening elements, may be, and preferably are, employed to effect rigid connection as between the base plate and the lip or flange, though it is to be understood that in some instances the portions herein referred to 45 as lips and base plates, may be of integral formation.

In order that inaccurate impingement of air jets upon the blank (such as is often the result of vibration of the machine), 50 may be eliminated, I form medially of and at the lower end of the rear wall of the nozzle, an apertured ear 26 which, by means of a bolt or the like fastener, is rigidly connected to a fixed part 25 of the carrying frame, thereby minimizing the objections stated.

It will be noted by reference to Figs. 2 and 3, that longitudinal spacing of these slot-like orifices results in a creation of separate fan-like blasts of air, which at their points of contact with the suspended blanks being cooled, coact with each other in the formation of a relatively long, substantially flat, blast, which is of such width as 65 to effect chilling of blanks whether they

be carried by single, double or triple molds. Further, it will be noted that each nozzle is formed with two sets of these orifices uniformly spaced from the center, by reason of which, two, four or six blanks may 70 be simultaneously treated. At this point, it should be noted that each mold carrying unit or arm is to be provided with one of these nozzles, and that the molds may be of types to suspend, single, double or triple 75 charges of molten glass.

While I have quite specifically set forth the preferred form, it is understood that certain changes in details of construction, 80 may be resorted to without departing from the spirit of the invention as claimed.

What I claim is:

1. In a glass forming machine, means for chilling corresponding sides of a plurality of suspended charges of molten glass in 85 plastic form, said means comprising an elongated body having a longitudinally extending, relatively long, slot-like, jet orifice in one wall, and means for intermittently ejecting blasts from the orifice.

2. In a glass forming machine, means for chilling corresponding sides of a plurality of suspended charges of molten glass in plastic form, said means comprising an elongated body having a set of longitudinally spaced jet orifices along one wall, and means for intermittently ejecting blasts through 95 the orifices.

3. In a glass forming machine, means for chilling corresponding sides of a plurality of suspended charges of molten glass in 100 plastic form, said means including an elongated body having a set of longitudinally spaced forwardly declined orifices extending from the lower wall, and means for 105 intermittently ejecting blasts through the orifices.

4. In a glass forming machine, means for chilling corresponding sides of a plurality of suspended charges of molten glass in 110 plastic form, said means including an elongated body having a set of longitudinally spaced slot-like orifices along one wall.

5. In a glass forming machine, means for chilling corresponding sides of a plurality of suspended charges of molten glass in 115 plastic form, said means including an elongated body having a set of longitudinally spaced, horizontally flattened orifices, said orifices being declined forwardly from the 120 lower wall.

6. In a glass forming machine, means for chilling corresponding sides of a plurality of suspended charges of molten glass in plastic form, said means comprising an elongated 125 body having forwardly declined slot-like orifices communicating with its interior through the lower wall.

7. A nozzle for a machine of the character described, comprising an elongated hollow 130

body having a longitudinal slot-like orifice in one of its longitudinal walls, and an air inlet.

8. A nozzle for a machine of the class described, comprising an elongated hollow body having an air inlet, a forwardly projecting lip extending longitudinally of one wall and having longitudinally spaced, slot-like, orifices formed therein and communicating with the interior of said body.

9. A nozzle for a machine of the class described, comprising an elongated hollow body having an air inlet, a forwardly projecting declined flange along one vertical wall, a separable base plate secured to the lower side of said flange, said base plate having elongated, relatively flat, ways, forming orifices communicating with the interior of the body.

10. A nozzle for a machine of the class described, comprising an elongated hollow body having a centrally arranged inlet, a forwardly declined lip extending from the lower end of one vertical wall at each side of the inlet, and a base plate separably attached to the lower face of each lip and having longitudinally spaced, transversely extending, slots coacting with the adjacent faces of the lips to form orifices communicating with the interior of the body.

11. In a glass forming machine, the combination of means for forming and simultaneously suspending a plurality of blanks of plastic glass, means for supplying a plurality of air jets individual to the blanks and simultaneously directing said jets against the

respective blanks, and a single controlling device for simultaneously controlling the supply of air to said jets.

12. A glass forming machine comprising, in combination, a rotary mold carriage including a plurality of heads or units, a plurality of molds on each head for simultaneously forming a plurality of parisons, means for suspending the bare parisons, a cooling device associated with each of said heads, said device comprising means for supplying jets of air individual to the parisons and simultaneously directing said jets against the respective parisons, and a single controlling device for simultaneously cutting off the supply of air.

13. A glass forming machine comprising, in combination, a rotary mold carriage including a plurality of heads or units, a plurality of molds on each head for simultaneously forming a plurality of parisons, means for suspending the bare parisons, a cooling device associated with each of said heads, said device comprising means for supplying jets of air individual to the parisons and simultaneously directing said jets against the respective parisons, controlling devices individual to said heads, each controlling device comprising a valve by which the supply of air to all the jets on said head is controlled, and a stationary cam operable to actuate said valves in succession.

Signed at Toledo, in the county of Lucas and State of Ohio, this nineteenth day of February, 1926.

HAROLD A. ROHRICH.
